UNITED STATES PATENT OFFICE.

ARTHUR J. BRADLEY, OF OAKLAND, CALIFORNIA, ASSIGNOR TO S. T. JOHNSON CO., OF OAKLAND, CALIFORNIA.

FUEL-OIL FEED SYSTEM FOR CRUDE-OIL BURNERS.

Application filed August 24, 1926. Serial No. 131,228.

This invention relates to improvements in the oil feed system for crude oil burners.

The general aim of the present invention is to provide for the more efficient operation of the fuel-oil supply line to the burner atomizer, causing the flow of fuel-oil thru the atomizer to be more regular, continuous and uniform.

One of the objects of the invention is the provision of relatively simple and efficient means for controlling the delivery of fuel-oil to the burner atomizer especially at the moment of starting the burner operation.

Another object of the invention is the provision of a separator tank within the fuel-oil feed line to the burner, and the provision of means for filling said separator tank from a main storage reservoir by the use of a motor operated pumping system.

Another object is the provision of means for freeing the fuel-oil of air which has been absorbed thereby, and this is of especial value in the use of rotary burners using a pumping system.

To obtain this result, the rapid flow of oil must be caused to change its direction rather suddenly and be spread over an enlarged area, so that the particles of air, by means of their vis viva, assisted by their low specific weight will fail to follow the change of direction of the oil, but will separate therefrom.

The objects of the invention thus generally stated, together with other and ancillary advantages, are attained by the construction and arrangement illustrated in the accompanying drawings forming part hereof, wherein I have illustrated a practical embodiment of the invention, in which:—

Figure 1 is an elevational view of the fuel-oil lines to a rotary burner pump, including the discharging line from the pumping system with its connections to the storage reservoir and showing the location of the separator tank device connected within the fuel-oil return line;

Fig. 2 is a vertical sectional view taken through the separator tank device;

Fig. 3 is a top plan view of the separator tank device; and

Fig. 4 is a cross sectional view of the separator tank device on line IV—IV of Fig. 2.

Referring to the drawings, in which like reference characters are used to denote corresponding parts in the different views, the

letter S on Fig. 1, denotes a liquid fuel-oil separating apparatus interposed in the fuel-oil discharging line from the pump to the burner. A storage reservoir T, preferably placed underground, outside of the building, is connected with the pump P, by means of a suction line 10, preferably leading thru a primary strainer chamber 11, so that any particles of foreign matter will be arrested. The pump P is operatively connected to the burner motor shaft by means of a suitable interposed gear (not shown).

The separating apparatus S is constructed substantially as illustrated in Fig. 2. It consists of a single metallic casing member 12, slightly reduced in circumference at the top, as at 13, relative to the casing member 12, for the purpose of forming a fuel-oil receiving chamber 14 of reduced size, to be hereinafter described. This reduced part is closed at the top by means of a removable closing cap 15, secured in position by means of a yoke construction 16 provided with a set-screw 17. The casing member 12 forming the separating chamber 18.

Connection is made with the fuel-oil discharging line D, from the pump P, as at 19, by means of an oil conduit 20, formed integrally with the casing member 12, extending upwardly from the base thereof and provided with an inlet port 21 to said fuel-oil receiving chamber 14. An outlet port 22, positioned in the opposite direction from said inlet port 21, within said chamber 14, forms a passage by means of a pipe line 23, to the storage reservoir T, for returning thereto the major portion of the fuel-oil passing thru said chamber 14.

Formed interiorly, between the reduced fuel-oil receiving chamber 14 and the separating chamber 18, is a horizontal partition 24, provided with a centrally disposed opening to receive therein a circular reinforced strainer basket 25, said basket having a collar 26 at its upper end to form a retaining means for said basket within said opening. A handle 27, in the form of a loop is secured to said collar to facilitate the removal and replacement of the strainer basket.

The bottom of the chamber 18 is provided with a tubular boss 28, which is interiorly threaded to receive a threaded end of the fuel-oil feed line 29, thru which the fuel-oil is conducted to the burner.

A relief valve 30, is interposed in the

fuel-oil return line 23, serves the purpose of maintaining a certain back pressure within said separating chamber 18, being adjustable to suit varying conditions of service. The 5 working pressure on the oil within the chamber 18 may be disclosed by the gage 31.

In operation, the fuel-oil entering the separating apparatus at 19, thru the fuel-oil discharging line from the pump P, rises in 10 the conduit 20 and flows thru the receiving chamber 14 towards the fuel-oil return line port 22. In other words, the fuel-oil enters in an upwardly direction, and is then diverted horizontally therefrom towards the 15 circular strainer basket 25, from whose rim a part of the fuel-oil falls downwardly and passing thru the strainer is collected within the chamber 18. The major portion of the fuel-oil passing out thru the port 22 and 20 thru the relief valve 30, returning to the storage reservoir T. The oil thus flows in a continuous cycle, a certain regulated quantity being taken to the burner. The fuel-oil in passing into the strainer basket 25, is 25 thereby caused to change its direction of flow rather suddenly and is spread over an enlarged area. The particles of air contained in the fuel-oil tend to continue the forward course, because of their vis viva imparted by 30 the rapid flow of the oil, and because of their considerable lower specific gravity, will fail to follow the change of direction of the fuel-oil into the basket, but will separate 35 therefrom and pass out with the major portion of the fuel-oil returning to the reservoir.

The oil passing over the rim of the strainer basket 25 and into the same, is broken up sufficiently to cause a separation 40 of the air contained therein, the de-aerated fuel-oil is caused to pass to the burner under the fluid pressure created by the pump and by the back pressure maintained by the relief valve 30, so that the fuel-oil passes 45 evenly to the burner in a steadily flowing stream. A certain quantity of fuel-oil is always maintained within said chamber 18, thus securing a more regular, continuous and uniform oil delivery to the burner. This is 50 of considerable importance, especially on the starting of the burner, because the use of this device provides an immediately available supply of fuel-oil to the burner, not dependent upon the supply to be furnished 55 by the pump operated by the burner motor and very often resulting in a belated fuel-oil delivery.

An electrically operated fuel-oil stop valve E is provided in the fuel-oil feed line between the separating apparatus and the burner and is controlled by the switch in the electric circuit that operates the motor (not shown) the parts being arranged so that the valve is held open to permit the flow of fuel-oil to the burner so long as the current 60

passes to the motor and is closed to a positively shut-off of the fuel-oil supply to the burner when the motor stops. This valve furnishes a positive cut-off for the fuel-oil between the chamber 18 and the burner 70 atomizer, it prevents the passage of even a limited amount of the fuel-oil contained in the chamber of the separating apparatus to the burner when the motor stops. When the motor starts, this valve is simultaneously 75 opened for the flow of fuel-oil to the burner.

Obviously the construction is capable of modification and I do not wish to be limited except as indicated in the appended claims. 80

I claim:

1. In combination with a rotary oil burner, a fuel-oil reservoir, a pumping system, a fuel-oil line leading from said reservoir to said pumping system, a fuel-oil discharging line from said pumping system to the burner, a separating device interposed in said discharging line thru which a part of the fuel-oil drawn from the reservoir is fed to the burner and the major portion returned to 90 said reservoir; said separating device comprising a single metallic casing formed with a circumferentially reduced upper part and having a removable cover-cap associated therewith, said part forming a receiving chamber of reduced size, a vertically disposed oil conduit interior of said casing and integral therewith, communicating with said receiving chamber, a fuel-oil return outlet 95 provided in said receiving chamber and leading to the reservoir, a horizontal partition within said receiving chamber provided with an opening to receive a strainer basket extending downwardly and centrally within said casing, thus acting on the fuel-oil as it emerges from the oil conduit to 100 effect a sudden change in its direction of flow thru said strainer basket, an outlet port in the bottom of said casing in communication with the fuel-oil feed line to the burner. 110

2. In combination with a rotary burner, a fuel-oil reservoir, a pump, a fuel-oil line leading from said reservoir to said pump, a fuel-oil discharging line from said pump to the burner, a separating device interposed in said discharging line thru which a part of the fuel-oil drawn from the reservoir is fed to the burner and the major portion thereof returned to said reservoir; said separating device comprising a single metallic casing, forming a main fuel-oil chamber and formed with a contracted upper part, said contracted part having a removable top cover associated therewith and forming a receiving chamber of reduced size, a vertically disposed fuel-oil conduit interior of said casing in communication with said receiving chamber, to receive a mixture of fuel-oil and air to direct it upwardly into said receiving chamber, a horizontal partition between said 120 125 130

- chambers, a strainer basket suspended from said horizontal partition, said mixture having its direction of flow quickly changed in passing thru said strainer basket to separate 5 the air from the fuel-oil, an outlet port for the air and surplus fuel-oil in said receiving chamber, a pressure responsive relief valve controlling the flow of the fuel-oil and air thru said outlet port, an outlet for the de- 10 aerated fuel-oil in the bottom of said main fuel-oil chamber in communication with the feed line to the burner and means associated with said feed line to shut-off the flow of fuel-oil from said chamber.
- 15 3. In combination with a rotary burner, a fuel-oil supply reservoir, a pump, a fuel-oil line leading from the reservoir to said pump, a fuel-oil discharging line from said pump leading to a separating device, a surplus fuel- 20 oil return line connecting said separating device with said reservoir; said separating device comprising a receptacle having a main fuel-oil chamber and a reduced fuel-oil receiving chamber on the top thereof, said 25 chambers separated by a horizontal partition, a closing cover for said reduced chamber, a fuel-oil conduit between the discharging line of said pump and the said receiving chamber, a surplus fuel-oil return line leading 30 from said receiving chamber to the reservoir, a fluid pressure responsive valve interposed in said fuel-oil return line controlling the return flow, said partition provided with an opening to receive a strainer basket 35 whereby the fuel-oil entering the receiving chamber, by the pump pressure, is caused to pass in part thru said relief valve and hence to the reservoir, while a smaller portion is caused to first change its direction of flow to pass thru said strainer basket into the main 40 fuel-oil chamber, an outlet provided in the bottom thereof communicating with the burner feed line.
4. In combination with a rotary oil burner, a fuel-oil reservoir, a pump, a fuel-oil line leading from said reservoir to said pump, a fuel-oil discharging line leading from the pump to a separating device, a surplus fuel-oil return line leading from this separating device to said reservoir; said separating device comprising a receptacle having a main fuel-oil chamber and a reduced fuel-oil receiving chamber superimposed thereon, said chambers separated by a horizontal partition, a removable cover plate for 50 said reduced chamber, a fuel-oil conduit connecting the discharging line from the pump with said receiving chamber, a surplus fuel-oil line leading from said receiving chamber to the reservoir, a fluid pressure responsive relief valve interposed in said fuel-oil return line controlling the return flow from 55 said receiving chamber, said horizontal partition provided with an opening to receive a strainer basket, whereby the fuel-oil entering the receiving chamber is caused to pass in part thru said basket into the main fuel-oil chamber, while the major portion is caused to return thru said relief valve to the reservoir, a fuel-oil feed line leading from the bottom of said chamber to the burner, means associated with said feed line to shut-off the flow of fuel-oil to the burner when not 60 in operation.

In testimony whereof I affix my signature.

ARTHUR J. BRADLEY.
